PROCESS FOR THE MANUFACTURE OF AL-KALI HYDROXIDES AND APPARATUS FOR CARRYING OUT REACTIONS

George Ernest Edwards, Runcorn, England, assignor to Imperial Chemical Industries Limited, a corporation of Great Britain

Application July 9, 1941, Serial No. 401,687
In Great Britain August 28, 1940

13 Claims. (Cl. 23—184)

This invention relates to an improved process and apparatus for carrying out reactions involving liquid amalgams, that is, solutions or liquid alloys of metals (e. g. sodium) with mercury; and more especially for the manufacture of alkali metal hydroxides.

It is well-known that the amalgams of alkali metals can be reacted with water or with aqueous solutions. An important process for the manufacture of caustic soda is based on the reaction of electrically produced sodium amalgam with water. Various types of apparatus have been proposed to carry out this reaction; thus it has been proposed to flow the amalgam down vertical sheets, bands or gauzes of a metal such as iron immersed in the water. With such arrangements, however, difficulties have hitherto been experienced in avoiding irregularities in the feed to the different parts of the band or sheet and in setting the upper edge of the supporting surface accurately level. Even if uniform initial distribution of amalgam on the surface is achieved, it frequently happens that due to surface tension effects, the distribution may become unequal lower down the surface, leaving parts of the surface unwetted by the amalgam. As a result, the output and efficiency have been seriously affected. Hence no vertical denuder of this type has yet achieved commercial success in spite of the advantages which such denuders possess in respect of saving of mercury, economy of floor space and compactness of design in comparison with those types employing an almost horizontal trough for contacting the amalgam with the aqueous liquid. The vertical type would also possess the advantage as regards conservation of heat when working at an elevated temperature.

According to the present invention, the above mentioned difficulties are largely avoided or even entirely obviated by providing a process for reacting a liquid alkali metal amalgam with an aqueous liquid, e. g., water, or a dilute aqueous solution of an alkali metal hydroxide, in which the amalgam is contacted with the aqueous medium by allowing it to flow down the surfaces of a plurality of spaced vertical or steeply inclined amalgamated metal members of small cross-section, e. g., iron wires or narrow strips, immersed in the aqueous medium. Advantageously, the amalgam is fed to the amalgamated metal members from a vessel, e. g., a trough, by arranging the members to pass over the edge of the vessel into the amalgam therein in close proximity to each other so as to form channels in which the amalgam can be retained by capillary attraction, and

5 maintaining the level of amalgam in the vessel such that the amalgam can rise in the said channels to the edge of the vessel, and thus pass to the downwardly-extending surfaces of the amalgamated members. Alternatively, or, in addition, the members may pass into the vessel in close proximity to its sides, which latter are capable of being wetted by the amalgam so that capillary channels for the amalgam are formed between the members and the sides of the vessel.

10 According to a further feature of the invention apparatus for carrying out the above process comprises in combination a reaction vessel, a trough horizontally disposed at the upper part thereof, means for supplying amalgam to the trough, means for regulating the level of the amalgam in the trough, a plurality of closely spaced members of small cross-section of a metal capable of being wetted by the amalgam extending 15 at least to the level inside the trough at which the amalgam is maintained, over the edge of the trough, and thence downwards into the lower part of the vessel, means for supplying to the reaction vessel the aqueous medium to be contacted 20 with the amalgam, means for withdrawing the treated aqueous medium, and means for withdrawing denuded amalgam. Preferably the members are in close proximity to the side of the trough over the edge of which they pass and that side is capable of being wetted by the amalgam.

25 In accordance with the present invention a number of separate paths are provided by the narrow spaces between the amalgamated surfaces of adjacent metal members in which the amalgam is retained by capillary attraction, which also ensures that the amalgam will not be diverted from one channel to the other, leaving part of the surfaces incompletely wetted as may 30 be the case when vertical sheets or gauzes of metal are used for the purpose. Moreover, irregularities in the feed, or inaccurate levelling of the trough will not seriously affect the distribution 35 of amalgam to the supporting surfaces. In the preferred form of the invention capillary channels are also formed between the wires and the sides of the trough, thus increasing the capacity of the apparatus.

40 If desired, a number of troughs can be arranged in parallel close to each other in the same apparatus, each trough being fitted with a set of closely spaced wires dipping into it; each trough may 45 have a separate feed for amalgam, or all the troughs may be supplied with amalgam from a common distributing device. In this way a com-

pact apparatus with a comparatively large capacity can be obtained.

In one form of the invention as applied to the manufacture of caustic alkalies the apparatus consists of a deep tank of rectangular cross-section, in the upper part of which a horizontal trough is arranged parallel to the long side of the rectangle, and within which trough is a horizontal bar adjustable in a vertical direction. In the lower part of the tank and in substantially the same vertical plane as the trough is a second fixed horizontal bar. Amalgamated vertical iron wires pass beneath the upper bar, over the edges of the trough and round the lower bar, being spaced apart from each other by approximately 10 their diameter, which suitably may be of the order of 0.1 or 0.05 inch. The spaces between successive wires thus form capillary channels along which amalgam will be drawn. The wires may be separate, or one length of wire may be wound over the trough and lower bar many times to form a plurality of members, the ends of the wire or wires being in either case fixed, e. g., to the lower bar. By means of the vertical adjustment of the upper bar the wires can be made sufficiently taut to steady them in position, and they can be bent downwards within the trough below the level of the amalgam therein. Between the sides of the tank and the vertical wires are carbon blocks either in direct contact with the wires or separated from them by a short distance, and in electrical contact with them by means of internal or external connections.

Means are provided for feeding a liquid alkali metal amalgam to the trough through a regulating device from a stock tank or direct from the electrolytic cell in which it is made, and for withdrawing denuded amalgam from the bottom of the tank for return to the cell. A weir and overflow may be provided for regulating the level of amalgam in the trough or alternatively this regulation may be achieved by a valve, a niveau or equivalent means in the amalgam supply pipe. In the lower part of the tank an inlet pipe for water or caustic liquor is provided and slightly above the level of the trough an outlet for the caustic liquor produced. Alternatively, when higher strength caustic liquor is required a circuit including a pumping mechanism may be set up, whereby the effluent caustic liquor is returned to the lower part of the tank, means being also provided for bleeding off part of the caustic liquor leaving the tank, and for introducing to the lower part of the latter a corresponding amount of water. In many cases, however, the re-circulation system will not be necessary, for a strong liquor can be obtained by one passage through the apparatus. For example, in the manufacture of caustic soda a liquor containing 45% to 50% NaOH can be obtained without recirculating.

In using this apparatus the tank is filled with water or dilute caustic liquor and amalgam is delivered to the trough until the lowest part of the wires in it are covered, and the level of the amalgam is such that it is able to travel along the spaces between the amalgamated wires bent over the trough up to the edge of the latter and thence down the descending portions of the wires; the supply of amalgam is then maintained at such a rate that denudation of the amalgam is substantially complete by the time it has travelled to the bottom of the tank. In practice it is found that a considerable variation in the flow of amalgam is possible while still maintaining an operative level in the trough, and thus no difficulties are

encountered in setting up a flow which both enables denudation to be substantially complete when the amalgam reaches the bottom of the tank and maintains a suitable level of amalgam in the trough.

The accompanying drawing illustrates a vertical transverse section of an apparatus for carrying out the invention.

In this drawing, the reaction vessel 1, which is deep in comparison with its cross-section, has in its upper part a horizontal trough 2 maintained in position by supports 3. The trough has one side 4 with a lip 5 extending the length of the trough and projecting inwardly and upwardly, the thickness of the lip forming a surface 6 over which wires pass, as will be explained hereinafter. The rear side 7 of the trough is higher than lip 5, and thus amalgam in the trough cannot seep over it. Inside the trough is a vertical bar 15 having its lower edge below the level of lip 5. In the lower part of vessel 1 vertically below the trough are two rods 9 acting as spacer bars for the wire 8, and bar 10 vertically adjustable by means of the screw thread and lock nuts 11. Wire 8 which provides the downwardly extending paths for the amalgam has one end (not shown) fixed to one end of bar 10 and is wound helix-wise around bar 10 and trough 2 so that each turn passes under bar 10, over the edge of side 7, under bar 15, over and in contact with surfaces 6, 5 and 4, and then vertically downwards to pass again under bar 10 and so on. The second end of the wire is fixed to the second end of bar 10. The turns are spaced apart by approximately the diameter of the wire, so that extending downwards from face 4 are a large number of lengths of wire, the various spaces between adjacent ones constituting separate paths for amalgam extending from inside the trough, over the lip 5, and thence downwards through the reaction vessel 1.

Reaction vessel 1 has an inlet 16 for water or dilute caustic alkali and an outlet 18 for denuded amalgam in its lower part, and in its upper part approximately at the level of trough 2 is an outlet 17 for the caustic alkali produced. Between the vertical wire 8 providing the paths for the amalgam and the side of reaction vessel 1 is disposed a block of graphite 12 to promote the decomposition of the amalgam by the aqueous liquor; the block is fixed to the vessel 1 by bolts 13 and metal strips 14, are provided in good electrical contact with bolts 13 and the outside of reaction vessel 1. The graphite block is thus indirectly in electrical communication with the amalgam through bolts 13, strips 14, reaction vessel 1, support 3 and trough 2. Means, not shown, are also provided for delivering amalgam to the trough 2 and for regulating the supply so as to maintain a suitable level in the trough.

In carrying out the process with the aid of this apparatus, the surfaces 4, 5, 6 and the surfaces of wire 8 are amalgamated, water or dilute caustic alkali is supplied to the vessel 1 so as to fill it up to the level of outlet 17, and amalgam is supplied to the trough up to somewhat above the lower edge of face 6 of the lip 5. As the result of capillary attraction the amalgam is drawn up in the narrow channels between the flat surface 6 and the rounded surfaces of the adjacent turns of the wire 8, and thus reaches the join of faces 6 and 5. The amalgam then flows downwards still held by capillary attraction between adjacent turns of the wire, so that in effect it is siphoned over the edge of the trough.

In travelling down between the wires the amalgam is denuded by reaction with the aqueous caustic alkali in the vessel 1, and on reaching the part of the wire curtain between the spacer bar 9 and the bottom bar 10 the denuded amalgam will fall from the wires to the bottom of the tank and can be drawn off through exit 18. The flow of amalgam and of caustic alkali are regulated relative to one another so that optimum denudation of the amalgam is obtained while a concentrated liquor can be drawn off at the caustic liquor outlet 17.

It will be appreciated that various alterations may be made in the apparatus and in its mode of operation without departing from the spirit of the invention. Thus instead of having one wire 8 passing many times into trough 2 and under bar 10, a number of separate wires may be used, one end of each being fixed to bar 15, and the other to bar 10. On the other hand, both sides of trough 2 may be arranged to deliver amalgam to wires passing over them down into the tank.

Again, instead or in addition to graphite block 12, a similar graphite block may be inserted on the other side of the wires to which amalgam is supplied, i. e., in the space immediately beneath the trough 2.

Although the invention has been described with reference to the production of caustic alkalies the apparatus may be used to carry out other processes for reacting liquid amalgams with aqueous liquids, e. g., for reducing aqueous solutions of organic compounds, for reducing sulphites to hydrosulphites, or for reducing alkali metal polysulphide solutions to sulphide solutions. In such cases, however, the carbon blocks acting as depolarizing devices described in connection with that form of the invention illustrated in the accompanying drawing will not, in general, be required.

In my related copending application Serial No. 401,886 of even date with this application there is described a process and apparatus for carrying out reactions involving liquid amalgams, in which the amalgam is fed to a downwardly extending supporting surface by siphoning the liquid amalgam over the upper edge of the surface from an adjacent trough containing a supply of the amalgam along a plurality of independent passages reaching from the amalgam supply to a lower level on the supporting surfaces. The independent passages are advantageously capillary channels formed between adjacent amalgamated surfaces of metal members of small cross section, or between such members and an adjacent amalgamated surface.

I claim:

1. The process for carrying out continuous reaction between a liquid amalgam and a reactive fluid, comprising the operation of causing liquid amalgam to flow down continuous exposed capillary channels disposed side by side and closely spaced laterally from each other, and bringing said reactive fluid into contact with the amalgam while flowing in said channels.

2. The process of reacting a liquid alkali metal amalgam and a reactive fluid selected from the group consisting of water and a dilute aqueous alkali metal hydroxide solution, which comprises submitting the amalgam to reaction conditions by causing it to flow down the surface of a plurality of amalgamated metal members of small cross section arranged side by side and spaced from each other laterally with substantially clear

passages therebetween and extending downwards in a body of the reactive fluid, whereby a large total surface of amalgam is exposed to the reactive fluid.

3. The process of reacting a liquid alkali metal amalgam with a reactive fluid selected from the group consisting of water and a dilute aqueous alkali metal hydroxide solution, which comprises submitting the amalgam to reaction conditions by causing it to flow down capillary channels formed between adjacent individuals of a plurality of closely spaced amalgamated metal members of small cross section substantially vertically disposed with intervening substantially unobstructed passages and extending downwards, while bringing the reactive fluid into contact with the amalgam in said channels.

4. The process of submitting a liquid amalgam to reaction conditions, which comprises causing the amalgam to rise from a supply thereof by capillary action in a plurality of closely adjacent open paths and then to flow downwardly in open closely adjacent paths longer than the rising paths and in continuation of the latter.

5. The process of reacting a liquid amalgam with a reactive fluid, which comprises causing the amalgam to rise from a supply thereof by capillary action in a plurality of closely adjacent open paths and then to flow downwardly in open closely adjacent paths longer than the rising paths and in continuation of the latter, and contacting the amalgam with the reactive fluid during its downward flow.

6. The process of reacting a liquid amalgam with a reactive fluid, which comprises causing the amalgam to rise from a supply thereof by capillary action in a plurality of closely adjacent open paths and then to flow downwardly in open closely adjacent paths in continuation of and longer than the rising paths in contact with the reactive fluid until the amalgam is substantially denuded.

7. An apparatus for carrying out a reaction between a liquid and a reaction fluid in a continuous manner, comprising a tank, an inlet at one level for supplying reactive fluid to the tank, an outlet at a different level for removing reacted fluid from the tank, a curtain of members of small cross-section wettable by the liquid extending downwardly in the tank between the two said levels, said members being disposed side by side and closely spaced laterally from each other to define therebetween capillary channels in which the liquid can be retained by surface tension, and means for supplying the liquid to the top portion of said curtain.

8. An apparatus for feeding a liquid to a reaction zone, comprising a trough having one side terminating upwardly in a horizontal edge, and being adapted to contain the liquid at a maintained level below the said edge, and a plurality of members of small cross-section wettable by the liquid disposed side by side in laterally spaced relation to define capillary channels therebetween, which members extend from the trough below the said level over the said edge and downwardly outside the trough to below the said level, the extent of said members above said level being such that the liquid can rise by capillary action between them and flow over said edge.

9. An apparatus for reacting a liquid with a reactive fluid, comprising a tank, an inlet at one level for supplying reactive fluid to the tank, an outlet at a different level for removing reacted fluid from the tank, a trough in the upper por-

tion of said tank having one side terminating upwardly in a horizontal edge and being adapted to contain the liquid at a maintained level below said edge, and a plurality of members of small cross-section wettable by the liquid disposed side by side in laterally spaced relation to define capillary channels therebetween, which members extend from the trough below the said maintained level, over the said edge, and downwardly to the lower part of the tank, the extent of said members above the said maintained level being such that the liquid can rise by capillary action between them and flow over said edge.

10. An apparatus for feeding a liquid from an open vessel adapted to contain the same at a maintained level, comprising a plurality of side by side elongated members of small cross-sectional area wettable by the liquid and extending upwardly from the vessel below the maintained level to a point above it and then downwardly outside the vessel to below said level, said members being disposed closely together so as to define capillary passages between them, and the extent of said members above said level being such that capillary action will cause the liquid to rise between said members to the highest point thereof.

11. An apparatus for feeding a liquid to a reactive fluid comprising a trough for the liquid having a horizontal edge, a tank below said trough adapted to contain the reactive fluid, a plurality of separate members of small cross-sectional area wettable by the liquid leading from within said trough over the horizontal edge and downwardly into the tank, said plurality of

members being in such laterally spaced relation that capillary action will cause the liquid to rise over said horizontal edge for gravity flow down and between the parts of the said members within in the tank.

12. An apparatus for feeding a liquid to a reactive fluid comprising a tank adapted to contain said fluid, a trough for the liquid in the upper part of the tank having a horizontal edge, and a plurality of separate members of small cross-sectional area wettable by the liquid leading from within said trough over the horizontal edge and downwardly into the lower part of the tank, said plurality of members being in such laterally spaced relation that capillary action will cause the liquid to rise over said horizontal edge for gravity flow down and between the said members into the lower part of the tank.

13. An apparatus for feeding a liquid to a reactive fluid comprising a tank adapted to contain said fluid, a trough for the liquid in the upper part of the tank having a side portion wettable by the liquid terminating upwardly in a horizontal edge, and a plurality of separate members of small cross-sectional area wettable by the liquid leading from within said trough over said horizontal edge, downwardly and in contact with said side portion, and thence into the lower part of the tank, said members being in such laterally spaced relation that capillary action will cause the liquid to rise over said edge for gravity flow down and between said members into the lower part of the tank.

GEORGE ERNEST EDWARDS.
